UNITED STATES PATENT OFFICE.

GEORGE M. WILLIS, OF CHICAGO, AND ARTHUR H. BOETTCHER, OF EVANSTON, ILLINOIS, ASSIGNORS TO MILWAUKEE GAS SPECIALTY COMPANY, OF MILWAUKEE, WISCONSIN, A CORPORATION OF WISCONSIN.

GAS IGNITER.

Application filed April 27, 1923. Serial No. 634,952.

To all whom it may concern:

Be it known that we, GEORGE M. WILLIS and ARTHUR H. BOETTCHER, citizens of the United States, residing at Chicago and Evanston, respectively, both in the county of Cook and State of Illinois, have invented a certain new and useful Improvement in Gas Igniters, of which the following is a full, clear, concise, and exact description, reference being had to the accompanying drawings, forming a part of this specification.

Our invention relates to gas stoves and similar devices; and more specifically to an improved accessory for igniting the flame of any burner of a gas stove without the use of matches.

In the stoves in the prior art having certain predetermined arrangements of burners, it has been found practicable to employ a fixed projector, designed to throw a fine jet of flame to each burner. There are, however, some stoves on the market in which the arrangement of the burners is such that a suitable set of jets reaching all the burners can scarcely be delivered by a fixed projector. For such stoves a movable projector is desirable, and it is the object of our invention to provide a movable projector device for such stoves and, indeed, if desired, for all adaptable stoves whether or not fixed burners are adaptable to them.

The difficulty with movable projector devices is that of leaking, particularly after it has been in service for a time, and the provision of such a device which will not leak, in which the gas will not have to pass or be retained by a rotary or other moving joint and which will stand the drastic test of use under actual service conditions is the primary object of the invention.

Further objects and advantages will become apparent as the description proceeds.

In the accompanying drawings;

Figure 1 is a more or less diagrammatic plan view of a gas stove in which the burners are so arranged that suitable service by a fixed projector is unobtainable;

Figure 2 is a much enlarged longitudinal view, principally in section, on a scale approximately twice actual size, to facilitate in clearly illustrating the details of the invention;

Figure 3 is a plan view of the structure illustrated in Figure 2;

Figures 4 and 5 are sections on line 4—4 and 5—5 respectively of Figure 2;

Figure 6 is a detailed side elevation of the actuating head; and

Figure 7 indicates a modification.

In the embodiment of the invention selected for illustration in Figures 1 to 6 inclusive, the valve casing 10 is provided with the inlet passage 12, the bore 14, the exit passage 16 and the bleed 18 for permitting sufficient flow at all times to maintain a tiny tip of flame. Valve 20 engages valve seat 22 to cut off flow to the main passage and its stem 24 passes through gland 26 provided with a suitable packing 28 and carries the actuating head 30 normally held in the position shown by compression spring 32, which spring also operates to maintain packing 28 in proper condition. Collar 34 may be adjusted to determine the extent of opening obtained when head 30 is manually depressed. The foregoing parts as above described are old and well known in the art, being disclosed in U. S. Patent 1,227,078 to Arnold O. Rutz, May 22, 1917, and per se form no part of the present invention.

Gland 26 is provided with a flange 34 held in fixed position with respect to casing 10 by reason of shoulder 36 which positions the entire gland. The projector 38 is carried at the end of arm 40, which arm underlies flange 34 to afford a mounting for its pivotal movement about the axis of the gland. The arm projects rearwardly to form a handle 42 by means of which the arm and projector may be swung to point at any burner desired.

Suitable flexible conduit means are provided for delivering gas from exit passage 16 to the projector 38. We have illustrated a rigid conduit 44 carried in blocks 46 suitably mounted on the underside of arm 40 as by means of fastening screws 48, and a relatively short flexible connection 50 extending from the proximate end of conduit 44 to the fitting 52 by means of which it is placed in communication with passageway 16. It will be apparent that arm 40 covers and protects the conduit placed below it, and it may be curved as clearly shown in Figures 4 and 5 to render it more rigid and improve its ability to protect the conduit.

Projector 38 is preferably provided with

a central aperture 54 and two side apertures 56, so as to throw three slightly diverging jets. This results in ignition of the entire extent of the burner more quickly and certainly, and furthermore materially decreases the accuracy with which the arm must be pointed in the direction of the burner.

Referring now to Figures 2 and 6, we provide a peripheral groove 58 having a central downwardly offset portion 60 in the lower sleeve of head 30. A set screw or pin 62 fixed in the telescoping portion of gland 26 enters slot 58, and a small bracket arm 64 projects laterally from head 30 to pass through a slot 66 in handle 42. When these features of construction are embodied, it will be obvious that head 30 will rotate with arm 40, and that except when pin 62 is in the offset portion 60 the valve will be depressed and a jet of flame for ignition purposes will be delivered from the projector. The position of the depressed portion 60 obviously coincides with the normal position of the device when not in use, and it is no longer necessary for the operator to depress head 30 at any time. It is only necessary to swing the arm 40 to point at the burner to ignite the same and complete the operation of the device. As the jet usually is a bright, white flame, there is no danger that it will be accidentally left in operation, as the operator's attention will be directed to the same until the parts are turned back to normal position. We also preferably provide a coil spring 74 mounted on the casing and engaging a pin 76 projecting from the under side of arm 40, to resiliently return the arm to normal position.

Without further elaboration, the foregoing will so fully explain the gist of the invention, that others may, by applying current knowledge, readily adapt the same for use under various conditions of service.

It will, for instance, be obvious that the entire valve casing might be pivoted instead of merely the projector and its supporting means, in which case it would be supported on a fixed bracket 68, see Figure 7, and connected to the main supply pipe 60 by flexible conduit 72. Similarly pin 62, bracket arm 64, spring 74 and the extra orifices 56 may be omitted if desired. These and many other modifications and adaptations may readily be made without eliminating certain features which may properly be said to constitute the essential items of novelty involved, which items are intended to be defined and secured to us by the following claims.

We claim:

1. In a gas igniter, in combination, valve mechanism, a pivotally mounted projector, a flexible conduit connection between said valve mechanism and said projector to per-

mit the latter to be swung, and automatic means for opening said valve when said projector is swung.

2. In a gas igniter, in combination, a valve, an extension arm pivoted on said valve, a conduit housed under said arm, a projector at the remote end of said conduit, and a flexible conduit connection between the proximate end of said first mentioned conduit and said valve. 75

3. In a gas igniter, a valve casing, a valve and valve seat in said casing, a stem projecting from said casing for exterior control of said valve, a gland for said stem, an external flange on said gland spaced from said casing, and an arm pierced by said gland and rotatable about the axis thereof, said arm lying between said casing and flange and being thereby held in place, a firing head carried by said arm and a flexible conduit connecting said casing and said head. 80 85

4. In a gas igniter, in combination, a member having an opening therein, a stationary valve housing, a supporting arm pivotally mounted relative to said housing and carrying said member, duct means including a flexible portion connecting said member with said housing, and a valve in said housing controlling the admission of 95 gas to said duct means.

5. In a gas igniter, in combination, a member having an opening therein, a stationary valve housing, a supporting arm pivotally mounted relative to said housing 100 and carrying said member, duct means including a flexible portion connecting said member with said housing, a valve in said housing controlling the admission of gas to said duct means, and a restricted bypass 105 around said valve.

6. In a gas igniter, in combination, a member having an opening therein, a stationary valve housing, a supporting arm pivotally mounted relative to said housing 110 and carrying said member, duct means connecting said member with said housing, said duct means including a flexible portion having one of its ends sealed to said movable member and the other of its ends sealed to said housing, and a valve in said housing controlling the admission of gas to said duct means. 115

7. In a gas igniter, in combination, a member having an opening therein, a stationary valve housing, a supporting arm pivotally mounted relative to said housing and carrying said member, duct means connecting said member with said housing, said duct means including a flexible portion having one of its ends sealed to said movable member and the other of its ends sealed to said housing, and a valve opening and closing by translatory movement. 120

8. In a gas igniter, in combination, a 130

member having an opening therein, a stationary valve housing, a supporting arm pivotally mounted relative to said housing and carrying said member, duct means including a flexible portion connecting said member with said housing, a valve in said housing controlling the admission of gas to said duct means, automatic connections for opening said valve when said movable member is displaced from a predetermined position, and resilient means tending to return said member to said position.

9. In a gas igniter, a valve casing having a chamber and a gas inlet and a gas outlet for said chamber, a valve seat between said inlet and outlet, a valve cooperating with said valve seat, means for operating said valve, a supporting arm pivoted to said casing, a projector carried on said supporting arm, and duct means including a flexi-

ble portion directly connecting said projector and said gas outlet.

10. In a gas igniter, a valve casing having a chamber and a gas inlet and a gas outlet for said chamber, a valve seat between said inlet and said outlet, a valve cooperating with said valve seat, said valve moving toward and away from said seat by translatory motion, a supporting arm pivoted to said casing, a projector carried on said supporting arm, duct means including a flexible portion directly connecting said projector and said gas outlet, and means operatively connecting said arm and said valve for effecting translatory movement of said valve by angular movement of said arm.

In witness whereof, we hereunto subscribe our names this 21st day of April, 1923.

GEORGE M. WILLIS.

ARTHUR H. BOETTCHER.
